Peter Caird, Santa Rosa, Calif., assignor to
Clarissa E. Caird, Santa Rosa, Calif.

Application September 8, 1952, Serial No. 21,382

Term of patent 14 years

(Cl. D91—3)

To all whom it may concern:

Be it known that I, Peter Caird, a citizen of Scotland, residing at Santa Rosa, county of Sonoma, and State of California, have invented a new, original, and ornamental Design for a Fire Hose Nozzle Unit, of which the following is a specification, reference being had to the accompanying drawing, forming a part thereof.

Fig. 1 is a side elevational view of a fire hose nozzle unit showing my new design; the opposite side being similar in appearance.

Fig. 2 is a front end elevation.
Fig. 3 is a rear end elevation.

I claim:

The ornamental design for a fire hose nozzle unit, as shown and described.

PETER CAIRD.
